Application January 17, 1939, Serial No. 251,412

2 Claims. (CL 204—87)

This invention relates to improvements in apparatus for electrolysis and methods of operating the same. More particularly the invention relates to improvements in the electrolytic preparation of chemicals from solutions of electrolytes.

Apparatus for use in the present invention are illustrated by way of example in the accompanying drawings in which:

Figure 1 illustrates apparatus in a system for operating an electrolytic cell for the preparation of chemicals;

Fig. 2 is a longitudinal substantially central sectional view of a cell unit for use in the above system;

Fig. 3 is a sectional view of the cell on line 3—3 in Fig. 2 in the direction of the arrows;

Figs. 4 and 6 are fragmentary views of the cell shown in Figs. 2 and 3;

Fig. 5 is a fragment of a plan view of one form of an improved gasket employed in the cell;

Figs. 7 and 8 are fragmentary views of modified means whereby the diaphragm in a cell is held in place without unduly interfering with the operation of the cell;

Figs. 9, 10, and 11 are sectional views of diaphragms adapted for use in the cell;

Fig. 12 is a top view of an end portion of a cell provided with improved means permitting withdrawal of liquid from the cell;

Fig. 13 is a longitudinal section of the cell through its end portion shown in Fig. 12;

Fig. 14 is an end view of the said improved means on the end of the cell shown in Fig. 12;

Fig. 15 is a vertical sectional view of a filter employed in the system shown in Fig. 1; and

Fig. 16 is a sectional view of the filter on line 16—18 of Fig. 15 in the direction of the arrows.

Like characters of reference are employed to denote similar parts in the several views.

In Fig. 1, the numeral 1 designates an electrolytic cell having appropriate electrical connections. Any suitable type of cell may be employed but in the electrolysis of sodium carbonate solution, for instance, to prepare sodium hydroxide and sodium bicarbonate, it has been found distinctly advantageous to use a cell of the type having a horizontal diaphragm. A preferred form of such cell will be described in detail below.

A tank or reservoir 2 is provided from which solution to be electrolyzed is fed to the cell 1, and to which electrolyzed solution is passed from the cell 1. For the electrolysis of an electrolyte solution such as sodium carbonate solution a cyclic process made possible by the use of the apparatus to be described is found to be highly

desirable. A given portion of the electrolyte solution is repeatedly passed through the cell at a regulated rate. The cell is equipped to permit continuous passage of electrolyte solution therethrough.

The tank 2 may be open at the top and may be provided with a conical bottom with an outlet pipe 3 having a valve 4. A feed pipe 5 provided with a valve 6 leads into the top of the tank. A pipe 7 having a valve 8 leads from adjacent the bottom of the tank 2 to a pump 9. The pipe 7 may have a portion 10 that extends into the tank 2 and that has its open end 11 positioned below the normal level of the liquid maintained in the tank.

The pressure side of the pump 9 is connected by a pipe 12 to an indirect heat exchange means 13 having inlet and outlet pipes 14 and 15 for heating fluid the flow of which is controlled by valves 16 and 17. A pipe 18 leads from the heat exchanger 13 to a filter 19. A filter of the type shown in Figs. 15 and 16 and described in detail below may be employed. A pipe 20 for the filtrate leads from the filter to the cell 1. Valve 21 in the pipe 18 may be used to control the passage of liquid to the filter 19. A pipe 22 having a valve 23 and connecting pipes 18 and 20, may serve as a bypass.

A pipe 24 provided with a valve 25 connects the cell 1 to the tank 2. An open end of the pipe 24 is positioned preferably below the level of the liquid in the tank 2 and adjacent a cooling coil 26 therein, having a valve 27 at its inlet end and a valve 28 at its outlet end for controlling the rate of circulation of the cooling fluid.

The pipes 20 and 24 are shown connected to the anolyte chamber of the cell. A pipe 29 is connected to the catholyte chamber of the cell 1 for the withdrawal of catholyte solution.

In the use of a cell having a horizontal diaphragm as distinguished from a cell of the filter-press type, provision may be made for the regulation of the rate of passage of the electrolyte through the pores in the horizontal diaphragm of the cell by means of apparatus for regulating the differential pressure of the gases generated at the cathode and at the anode. For this purpose means may be provided for the withdrawal of gases and for adjusting either the pressure of the gas in the anolyte chamber or the pressure of the gas in the catholyte chamber or both, depending on the desired rate of flow of the electrolyte through the diaphragm.

An example of the above regulating means is shown in Fig. 1. A pipe 30 connects the gas zone in the anolyte chamber of the cell 1 to a

chamber 31 communicating with the tank 2 by means of a pipe 32. A pipe 33 communicating with the gas zone in the catholyte chamber of the cell 1 leads to a chamber 34 that communicates with the tank 2 by means of a pipe 35. Liquid from the tank 2 passes into the chambers 31 and 34 and the level in each assumes the same position as the level in the tank. The ends of the pipes 30 and 33 are provided with extensible sections 36 and 37 respectively, joints for which are gas tight. The position of the open ends of the extensions 36 and 37 with respect to the level of the liquid in the chambers 31 and 34 respectively may thereby be varied and set to give any desired predetermined pressure differential which is indicated by a differential pressure gauge 38. One arm of the gauge is connected to the gas zone in the anolyte chamber of the cell 1 by a pipe 39, and the other arm is connected to the gas zone in the catholyte chamber by a pipe 40. The pressure in the anolyte chamber of a cell having a horizontal diaphragm may be maintained slightly higher than the pressure in the catholyte chamber by positioning the free open end of the pipe 36, a greater distance below the level of the liquid than the free open end of the pipe 37. The anode chamber pressure may be less than the cathode chamber pressure at times. Extensible pipes 36 and 37 serve to change the relative pressures consistent with proper feed.

In the operation of the apparatus shown in Fig. 1, sodium carbonate solution, for instance, is passed into the tank 2 through the pipe 5 and the level of the liquid is maintained above the cooling coil 26 and above the open end 11 of the pipe 10. The carbonate solution is withdrawn through the pipe 10 and then through the pipe 7 by the pump 9. The solution then flows through the heater 13 where it may be heated to a predetermined temperature of from about 60° C. to about 80° C. before conducting it into the anolyte chamber of the cell 1. The heated carbonate solution is passed into the cell and electrolyzed to form sodium hydroxide in the catholyte chamber and sodium bicarbonate in the anolyte chamber.

The carbonate solution is passed into the cell continuously through the pipe 20 and the anolyte and catholyte solutions are withdrawn from the cell continuously through the pipes 24 and 28 respectively. The feed and withdrawal to and from the anolyte chamber may be intermittent when desired. The valves 21 or 23 may serve to regulate the feed to the cell. The valve 25 in the pipe 24 may serve to regulate the withdrawal of anolyte solution from the cell. Recycling of the anolyte solution through a cell may be carried on with a given batch of carbonate solution until a satisfactory concentration of bicarbonate is obtained in the anolyte solution. The rate of passage of carbonate solution through a cell diaphragm may be regulated so as to obtain a substantial concentration of sodium hydroxide in the catholyte solution. Concentrations of sodium hydroxide up to about 25% may be obtained. The system may be regulated to obtain a preferred range of hydroxide of about 11% to about 18%. Ranges of concentration of hydroxide above 25% are apt to result in caking out of solid caustic on the cathode.

The catholyte solution from the cell withdrawn through the pipe 28 need not be recycled through the cell. In the use of a horizontal cell, a trap is formed in the pipe 28 to prevent escape of gas along with the catholyte solution. Any gases

withdrawn from the anolyte and catholyte chambers of the cell eventually pass through pipes 41 and 42 respectively to gas holders (not shown). In the electrolysis of sodium carbonate solution, hydrogen from the catholyte and oxygen from the anolyte chambers are obtained as valuable by-products.

The anolyte solution obtained by electrolyzing sodium carbonate solution and containing in the early stages of the cyclic operation sodium bicarbonate and substantial proportions of unconverted sodium carbonate, passes to the tank 2 from the cell 1 and is returned to the cell through the heater 13. Heating of the liquid passing to the cell tends to maintain the bicarbonate in solution and also tends to prevent convection currents in the cell. If desired, the tank 2 may be kept cooler than the cell to permit crystallization of sodium bicarbonate in the tank. For this purpose the cooling coil 26 may be used to cool the solution in the tank 2. Since bicarbonate has a lower solubility than carbonate, a saturated solution of the bicarbonate at a given temperature is obtained before a saturated solution of the carbonate at that temperature, and upon cooling below that temperature, there results a separation of the bicarbonate in the tank 2 in solid form. The solid bicarbonate settles to the bottom of the tank 2 and may be withdrawn through the valve 4 and passed into collectors.

By way of example, a desirable range of concentration of the sodium carbonate solution initially introduced in the system may be about 1½ pounds to about 2 pounds per gallon of water. With the use of a solution of such concentration the temperature may be brought down in the tank 2 within the approximate range of 25° C. to 28° C. The temperature in tank 2 may however be higher or lower than this range. The concentration of the bicarbonate in the system may in fact be controlled by controlling the degree of cooling in the tank 2. The lower the temperature below the point of saturation the more bicarbonate will separate out.

The system can be operated without cooling the liquid in the tank 2. In this case the liquid in the entire circulatory system may be maintained hot or at a predetermined temperature of around 60° to 80° C., and after a period of circulation the anolyte solution containing the bicarbonate can be cooled outside the cell to cause crystallization and separation of the bicarbonate in solid form. The solid bicarbonate may be separated from the mother liquor by filtration or settling, or it may be produced for use in the form of a slurry.

Liquid drawn from the tank 2 for recycling is preferably taken from near the liquid level and its rate of travel to and from the cell 1 may be regulated by the valves 8 and 25 respectively. Sodium carbonate solution may be added to the system through a pipe 43 having a valve 44 and connected to the pipe 7, or through the pipe 5 to maintain a constant level of liquid in the tank 2 and to keep the sodium concentration substantially the same in the solution delivered to the cell.

The solution level in the anolyte chamber of the cell 1 may be regulated during the recycling process by means of a swing joint 45 in the pipe 24. The swing joint comprises a short pipe connection inserted in the pipe 24, each end of which is connected by a swivel joint which permits raising and lowering of the end 45 to a

predetermined position above or below the end of the pipe 24 that is connected to the cell 1.

The liquid in the tank 2 may, when desired, be kept agitated. For this purpose a pump 46 may be provided having its intake connected to the pipe 7 and its pressure side connected to the top of the tank 2 by means of a pipe 47. The discharge end of the pipe 47 is preferably positioned at the solution level and enters on a tangent whereby a swirling motion of the liquid results during pumping. Recycling of the solution through the tank 2 may be conducted simultaneously with the recycling of the solution through the cell 1.

It is noted that a continuous cyclic means may be provided in the apparatus shown in Fig. 1. By this is meant that the said means make it possible to maintain liquid in the cycle in a substantially unbroken stream. The cycle may be maintained while electrolysis products are removed and while fresh electrolyte is added, and also, as in the horizontal type of cell, while any desired pressure differential is maintained in the anolyte and catholyte chambers.

An improved cell for use in electrolysis of sodium carbonate solutions and other electrolyte solutions in the cyclic apparatus shown in Fig. 1 will now be described. The cell illustrated in Figs. 2 and 3 comprises a casing within which a diaphragm 50 is horizontally supported between the anode and the cathode of the cell, thus dividing the cell into an anode chamber 51 and a cathode chamber 52. One important feature of the cell is the arrangement therein of the electrode surfaces, particularly of the anode, whereby means are provided for efficiently assisting in properly directing flow of the electrolyte solution and of the products of electrolysis. The construction and operation of this and other improved means will be specifically described below.

Rectangular frames 53 and 54, preferably shallow, serve to enclose the anode and cathode compartments respectively. The sides and ends of the frames 53 and 54 are constructed from steel L bars. The L bars in the frame 53 are welded to the top 55, and those in the frame 54 to the bottom 56 of the cell. The bars are tilted so that the flange 57 formed by the bars in the sides of the lower frame 54 slope downwardly away from the cell at an angle of about three degrees to the diaphragm 50. The flange 58 formed by the L bars in the sides of the upper frame 53 slope upwardly away from the cell at an angle of about three degrees to the diaphragm. The purpose of this construction is to make possible a tighter seal between the frames. The bottom frame is a little larger than the top frame so that when the frames are bolted together, the inner edge of the flange 57 effects a gripping action on the surface of the flange 58. The flange 58 overlaps the diaphragm and assists in holding the edges thereof in place. This arrangement furthermore provides a thoroughly leak-proof joint.

Bolt holes 59 and 60 (plan views Figs. 4 and 6), spaced a relatively short distance apart, are provided in the flanges 57 and 58 respectively, for bolts 61 screw-threaded at one or both ends. Nuts 62 and 63 on the bolts 61 serve to clamp the flanges tightly together. The bolts are insulated from one or the other of the flanges in any suitable manner as by means of a combined ring and gasket 64 fitting around the bolt and in the bolt

hole 60. Washers 65 and 66 are provided under the nuts 62 and 63 respectively.

The anode of the cell comprises a plurality of metal bars or slats 67 spaced a relatively short distance apart and extending from one side of the anode chamber 51 to the other, adjacent the diaphragm 50. Each of the bars 67 comprises preferably a flat steel rod or strip of a rectangular section (as shown in Fig. 2) and tilted to slope downwardly from its upper edge 68 to its lower edge 69 in the direction of flow of the electrolyte solution in the anode chamber 51. The entrances for the electrolyte solution being at 70 and 71, and the outlet for the anolyte solution being at 72, the bars 67 slope downwardly toward the exit 72. A fragmentary view of the anode frame looking upwardly from the diaphragm is shown in Fig. 6. The lower edges 69 of the bars 67 are preferably flush with the lower edge of the frame 53 from which the flange 58 extends. The upper edges 68 of the bars 67 may be below the level of the entrances 70 and 71 and outlets 72, and are preferably below the level 73 of electrolyte solution maintained in the anolyte chamber 51.

The upper edges 68 of the bars 67 at the ends thereof are welded to and abut against side bars 74 and 75 welded to opposite sides of the frame 53. The middle portion of each bar 67 abuts against and is welded to a bar 76 extending through the center of the anolyte chamber from one end thereof to the other. The bar 76 is welded to spaced blocks 77 which are in turn welded to the top 55 of the cell.

The bars 67 are tilted for the purpose of deflecting the electrolyte solution toward the diaphragm 50, as it flows through the anolyte chamber. A desirable angle of tilt is substantially thirty degrees to the horizontal.

The last cross bar 67' in the anolyte chamber 51 nearest the outlet 72 is preferably vertical and is spaced sufficiently from the frame wall to permit flushing of the diaphragm surface.

The cathode of the cell comprises a plurality of spaced metal rods or slats 80 of rectangular section in the catholyte chamber 52 and extending from side to side of the frame 54. The rods 80 are supported in a vertical position with the lower edge 81 of each resting at the ends on side bars 82 and 83 and welded thereto. The central portion of each rod 80 rests on a center bar 84 extending through the center of the catholyte chamber from one end thereof to the other. The center bar 84 is welded to a plurality of spaced blocks 85 and is supported thereby above the bottom 56 of the cell. The upper edge 86 of each rod 80 is preferably positioned slightly below the upper edge of the frame 54 thus providing space for a diaphragm between the anode bars 67 and the cathode bars 80. Spacers 87 and 88 are provided between the bars 80. A fragmentary plan view of the cathode frame is shown in Fig. 4.

A pair of terminals 90 passes through the top 55 of the cell and is welded to the center bar 84. A pair of terminals 91 passes through the bottom 56 of the cell and is welded to the center bar 84. The terminals 90 and 91 are placed so as to obtain uniform current distribution and are connected to the positive and negative terminals respectively of a current source.

Conduits 92 and 93 are connected to the anolyte and catholyte chambers 51 and 52 respectively. Connections such as pipes 39 and 29 shown in Fig. 1 may be made to these conduits for the purpose indicated above.

Various means made of compressible, corrosion

resistant insulating material may be employed for compressing the diaphragm 50 and for holding the latter in place while the cell is in operation. Referring to Fig. 5, a rubber sheet or alkali-resistant insulating means having a border 94 which serves as a gasket between the flanges 57 and 58, is provided with centrally disposed slots 95, and perforations 96 in the border. The border 94 is substantially wider than the flange 58 so that it extends into the cell past the wall formed by the frame 53 and overlaps the cathode bars 80 around the four sides of the cell, as shown in Figs. 2 and 3. In cooperation with the sloped flanges 57 and 58, the wide border 94 in the sheet makes it possible to have a thoroughly leak-proof cell. Furthermore the border 94 serves as insulation between the flanges 57 and 58. The strips or ribs 97 between the slots 95 lie crosswise of the cathode and anode bars 80 and 81 respectively and are pressed downwardly against the diaphragm 50 by the lower edges 89 of the bars 81. The perforations 96 are for the passage therethrough of the bolts 81. It is possible to provide perforations in the sheet in place of slots 95, but an objection to perforations is that they cause clogging due to eddy currents in the electrolyte as it passes through the cell.

Another form of diaphragm compressor means is shown in Figs. 7 and 8. Strips of rubber 98 or alkali-resistant material of relatively small width, and a thickness substantially that of the distance between the tilted bars 81 in the anode, are curled around the lower edge of each bar (as indicated in Fig. 7), the ends of a strip being inserted in adjacent spaces between the bars 81. The strips may be distributed as indicated in Fig. 8, which shows a portion of the anode looking upwardly from the surface of the diaphragm when the cell parts are assembled. In other words, the strips are placed in alignment from one end of the cell to the other in a plurality of rows which rows are spaced a relatively short distance apart. In alternate rows, R₁ and R₃ for instance, the strips are placed on alternate bars a, b, c, d, e, etc. In intermediate rows such as R₂, the strips are placed on alternate bars a', b', c', d', e', f', etc. With the strips in position the lower curved surface of each strip presses against the diaphragm of a cell. Each anode bar is thereby partially covered and insulated electrically. By means of the strip 98 it is possible to have active about 50% more of the surface of the bars 81 than in the arrangement shown in Fig. 5, and also at the same time obtain a more satisfactory mechanical construction.

Various means may be employed to serve as a diaphragm in the cell. A preferred form is shown in Fig. 9 in which the two layers of matted asbestos or preferably of asbestos paper 101 are placed between two layers of woven asbestos or of asbestos cloth 102. In Fig. 10, a form of diaphragm is shown with one layer of asbestos paper 101 between two layers of asbestos cloth 102. In Fig. 11, a form of diaphragm is shown in which the layers of fibrous material shown in Fig. 9 are placed on a wire screen 103 of about 8 mesh. If desired, the diaphragm shown in Fig. 10 may similarly be mounted on a wire screen which when mounted in the cell, rests on the cathode bars 80. The diaphragm and other means between the electrodes are clamped between the lower edges of the bars 81 and the upper edges of the bars 80 when the cell parts are assembled.

Figs. 12, 13 and 14 illustrate attachment means

for a cell of the type described above whereby flushing of the latter is made relatively simple and efficient. The discharge end of the anolyte chamber 105 through which an electrolyte solution is conducted, is provided with a rectangular port 106 in the end wall 107 of the said chamber and extending substantially across the width of the cell. A discharge hood 108, comprising side walls 109 and 110, a top 111 and bottom 112 projecting from the port 106 and each converging toward a relatively small end-wall 113, is welded to the end of the cell. The bottom 112 of the hood may rest on the flange 114 on the anode frame. Along the portion of the flange 114 covered by the hood 108, stud bolts 115 pass upwardly through the flange 116 on the cathode frame and are threaded into the flange 114. An insulation member 117 insulates the bolt 115 from the flange 116. Bolts 115 may be spaced the same distance apart as the other bolts 118 along other portions of the frames.

An outlet pipe 119 is provided in the end-wall 113 of the hood 108. This pipe corresponds to the pipe 12 (Fig. 2). When used in the system shown in Fig. 1 the pipe 119 may be connected to the pipe 24 by means of a swing-joint 45.

As shown in Fig. 13 when using the compression strips 98 on the anode bars 81 an insulating gasket 120 fitting between the frames may be employed. The gasket may be made of rubber or the like, or other substance, preferably unaffected by alkaline solutions.

The filter that may be employed in the cyclic system shown in Fig. 1 and designated by the numeral 19 may be constructed as shown in Figs. 15 and 16. By using two filters, one may be in use while the other is being cleaned. The filter shown comprises an outer casing 125, preferably cylindrical, having an inlet 126 adjacent one end and outlet 127 at or adjacent the other end. An inspection plate 128 is provided adjacent the inlet 126. Concentric with the casing 125 and with the outlet 127 is a perforated pipe 129 extending from the outlet end of the casing 125 to a relatively short distance from the inlet end. The pipe 129 is provided with a dead end 130. Concentric with the pipe 129, and of substantially the same length, is a cylindrical screen 131 which is reinforced by means of ribs 132. The space 133 between the screen 131 and the pipe 129 is filled with a filtering medium which may be any suitable granular or porous material. A satisfactory medium comprises two parts of sand and one part of asbestos fiber. This type of filter permits continuous passage of liquid therethrough. It is rugged enough to withstand the effects of plant usage. It can be readily cleaned by blowing live steam through it.

In the operation of the cell shown in Figs. 2-6, the liquid to be electrolyzed flows into one end of the anolyte chamber 51, as for instance, through the inlets 70 and 71. A continuous flow of liquid is preferably maintained through the anolyte chamber. The flow may, however, be intermittent, as indicated. As the liquid, brought to a level above the bars 81, proceeds towards the outlet 72 it is deflected toward the diaphragm 50. The electrolyte solution passes through the pores of the diaphragm and downwardly between the bars 80. The rubber compressor means 91 (or 98, Fig. 13) insure intimate contact between the cathode bars 80 and the diaphragm 50 which becomes saturated with and is maintained in constant contact with the electrolyte solution during the passage of current through the cell.

Gas from the anolyte chamber is withdrawn through the pipe 92. Gas generated at the cathode, and the catholyte solution flow from the cell through the pipe 93 and are permitted to separate. The gases may be used to effect a differential pressure on the diaphragm as described above.

A current density of about 0.40 to about 0.75 ampere per square inch may be employed in the electrolysis of sodium carbonate solution. Cells may be operated with about 200 to about 5000 amperes. A desirable current density has been found to be about 0.65 ampere per square inch; a desirable cell current is about 1000 amperes. A plurality of cells may be connected in series.

In providing the inclined anode bars 67 a sufficient number thereof is used in a cell to direct the flow of electrolyte properly therethrough as in a plurality of streams and to obtain uniform current distribution, and uniform contact of the electrolyte with the electrode. By properly tilting the anode bars, the formation of eddy currents in the flow of the electrolyte solution is diminished or substantially eliminated.

Other solutions besides sodium carbonate solution, namely potassium carbonate and sodium sulphate are effectively electrolyzed in the above cell and are suitable for treatment in the recycling apparatus shown in Fig. 1.

Reference is made herein to application Serial No. 87,569, filed June 26, 1936.

I claim:

1. An electrolytic process, comprising continuously and repeatedly circulating a solution of alkali metal carbonate, at substantially the temperature range of about 60° C. to about 80° C., through the anolyte chamber of an electrolytic diaphragm cell, said temperature being employed for maintaining in solution alkali metal bicarbonate electrolytically produced in the anolyte chamber, and while withdrawing from said latter chamber the resultant solution containing said electrolytically produced completely dissolved alkali metal bicarbonate and unconverted alkali metal carbonate subjecting the anolyte chamber and catholyte chamber to controlled differential pressure by means of separately entrapped gases from said chambers thereby effecting pas-

sage of some of the anolyte solution through the diaphragm and generating alkali metal hydroxide solution in the catholyte chamber of the cell to concentrations up to about 25% thereby avoiding caking out of solid caustic on the cathode, and in the course of said process separately withdrawing from the cell so-formed solution containing the alkali metal hydroxide, lowering the temperature of withdrawn solution containing alkali metal bicarbonate and alkali metal carbonate to effect solidification of alkali metal bicarbonate while maintaining the alkali metal carbonate in solution, and returning the alkali metal carbonate solution to the anolyte chamber of the cell for generation of additional alkali metal bicarbonate and alkali metal hydroxide.

2. An electrolytic process, comprising continuously and repeatedly circulating a solution of sodium carbonate, at substantially the temperature range of about 60° C. to about 80° C., through the anolyte chamber of an electrolytic diaphragm cell, said temperature being employed for maintaining in solution sodium bicarbonate electrolytically produced in the anolyte chamber, and while withdrawing from said latter chamber the resultant solution containing said electrolytically produced completely dissolved sodium bicarbonate and unconverted sodium carbonate subjecting the anolyte chamber and catholyte chamber to controlled differential pressure by means of separately entrapped gases from said chambers thereby effecting passage of some of the anolyte solution through the diaphragm and generating sodium hydroxide solution in the catholyte chamber of the cell to concentrations up to about 25% thereby avoiding caking out of solid caustic on the cathode, and in the course of said process separately withdrawing from the cell so-formed solution containing the sodium hydroxide, lowering the temperature of withdrawn solution containing sodium bicarbonate and sodium carbonate to effect solidification of sodium bicarbonate while maintaining the sodium carbonate in solution, and returning the sodium carbonate solution to the anolyte chamber of the cell for generation of additional sodium bicarbonate and sodium hydroxide.

H. L. STEWART.
